UNITED STATES PATENT OFFICE.

ALFRED S. CURTIS, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SET.

Application filed December 24, 1920. Serial No. 433,008.

To all whom it may concern:

Be it known that I, ALFRED S. CURTIS, a citizen of the United States of America, residing at New York, in the county of New York and State of New York, have invented certain new and useful Improvements in Telephone Sets, of which the following is a full, clear, concise, and exact description.

This invention relates to telephone sets in which the transmitter and receiver are mounted on a common support and particularly it relates to telephone hand sets.

It has long been known that when the receiver and transmitter of a telephone set are connected together upon a common handle, a noise often referred to as howling, is experienced when the instrument is placed in operation. This effect has heretofore prevented the use of highly efficient receivers and transmitters since they, by virtue of their higher efficiency, limit the conditions under which the sets may be used without howling. There are, at the present time, many types of hand sets in use, but investigation has shown that the efficiency of the transmitters and receivers used in connection therewith is necessarily considerably less than that of the instruments employed in the better type of desk or wall telephones.

It is the purpose of this invention to provide a hand set and the like which may be used with highly efficient transmitters and receivers and which will not tend to howl under the usual conditions of operation.

It has been found that the howling which takes place in telephone hand sets is governed by the relation of the uni-directional mutual impedance between the receiver and the transmitter to the transfer impedance between them through the electrical circuit.

The uni-directional mutual impedance, so called because it exists in one direction only, is defined as the ratio of the voltage generated in the transmitter, due to mechanical and acoustical vibrations communicated to it by the receiver, to the receiver current causing such vibrations. The transfer impedance is the ratio of the voltage generated in the transmitter to the current produced by it in the receiver. When the uni-directional mutual impedance is equal to the transfer impedance, sustained howling will take place. A decrease of the uni-directional mutual impedance will result in a corresponding decrease in the howling.

The variable factors which affect the ultimate value of the uni-directional mutual impedance are:

Impedance of the receiver,

Impedance of the transmitter,

Efficiency of the receiver,

Efficiency of the transmitter,

Mechanical construction of the set.

Heretofore no great attention has been paid to these several factors, with the result that only receivers and transmitters of comparatively low efficiency could be used in order to insure absence of howling. I have found that a hand set may be constructed in such a way that the uni-directional mutual impedance is kept within an allowable range even when highly efficient transmitters and receivers are used.

In general, the impedances of the receiver and transmitter are determined by the characteristics of the electrical circuits with which they are to be employed, and these are, therefore, considered as constant factors for the purpose of the present description.

The mechanical construction of the hand set directly affects the acoustic and mechanical coupling between the receiver and transmitter. The first is due to the agitation of the transmitter and diaphragm caused by the sound waves emitted by the receiver when variable current passes through it, and the other is due to the mechanical vibration of the receiver case transmitting vibrations through the handle to the transmitter. Due to the relative positions of the receiver and transmitter in a hand set the acoustic coupling is usually of too small a value to be of serious consequence. For this reason it is not considered herein.

The mechanical coupling through the handle is best expressed quantitatively as the ratio of the displacement of the transmitter end of the handle to the force at the receiver end producing it. Like the transfer admittance in an electrical circuit the mechanical coupling for sinusoidal forces is a complex operator possessing both magnitude and phase.

I have found that high mechanical coupling results from the mechanical resonance of the hand set or a part thereof. The reso-

nances other than those of the handle are due either to the vibration of the cases of the receiver and the transmitter, or to two parts which are connected together resonating with the elasticity of the joint connecting them.

The electrical circuits employed in substation equipments are so designed as to possess their lowest transfer impedance values 10 between a frequency range of approximately 600 and 1800 cycles per second, which is roughly the most important range of voice frequencies. In order to make the mechanical coupling low, it is necessary to prevent, 15 therefore, as far as practicable, all mechanical resonances within such frequency range.

By constructing the hand set in such a manner that all its mechanical resonances occur below 600 cycles, the mechanical coupling might be reduced to a minimum value. 20 This would necessitate the use of relatively heavy and flexible parts, and would produce a hand set which could not be readily adapted for use in ordinary telephone substations. 25 Moreover, the handle of such a hand set would possess a series of overtones which would fall within the frequency range stated above.

It is preferred, therefore, to make the 30 parts of the hand set light and rigid, to make the walls of the cases for the transmitter and receiver rigid, to make all of the joints between the various parts extremely tight to raise their elasticity, to so construct the 35 handle that its fundamental frequency of vibration is as high as compatible with the conditions imposed upon it by its use, and in this manner produce a hand set possessing a low mechanical coupling.

The vibration of such a handle under conditions of operation takes place in transverse waves, and the frequency of its fundamental mode of vibration or lowest frequency for standing waves, is approximately proportional to its radius of gyration in the direction of wave displacements and to the velocity of sound through the medium, the velocity of sound being proportional to the square root of the ratio of the volume modulus of elasticity of the material to its density. 40 In order to raise the fundamental frequency of the handle, it is necessary to employ a cross section having a large radius of gyration as stated above, or a material 45 with a high ratio of modulus of elasticity to density or a combination of the two. I have found that the fundamental mode of vibration of the handle should not be lower than approximately 1000 cycles per second.

In order to prevent mechanical resonance taking place in the walls of the instrument cases, it has been found necessary to make them relatively thick and rigid. The theory 55 of vibrating bells as discussed in "Theory of Sound," volume 1, by Lord Rayleigh, will

be found useful in designing cases having a definite frequency characteristic. The component parts of the cases also must be held tightly together. Moreover, wherever two flat surfaces are in contact, the surfaces 70 must be accurately made and the screws or other means employed for holding the parts together must be tight. In some cases it is desirable to employ a washer of paper or other yielding material between the parts 75 to take up any unevenness in the surfaces. The general expression for the frequency of vibrating joints is:

$$f = \frac{1}{2\pi} \sqrt{\frac{E}{M}} \quad 80$$

where f is the frequency, E the elasticity and M the mass.

I have found that there are at least three factors of considerable importance, which 85 determine the transverse wave transmission through the handle of the hand set. These are:

(1) The radius of gyration in the direction of the applied force in a cross section of 90 the handle, perpendicular to the neutral axis.

(2) The dimensions of such a cross section in a direction perpendicular to the above. 95

(3) The material of which the handle is made.

A suitable hand set may be formed by applying the well-known theory of vibrating bars, the general expression for which is 100

$$n = AK \sqrt{\frac{E}{P}}$$

where n is the frequency of the gravest mode of transverse vibrations, A a constant including the length which is essentially fixed by the head dimensions of the user, K the radius of gyration, E the modulus of elasticity and P the density. By the application 105 of this formula, the handle may be calculated for any uniform structure which may afterward be modified to suit the artistic sense providing the radius of gyration is not reduced. 116

The radius of gyration as expressed above, 115 should be as large as the construction of the hand set will allow. By increasing the cross section in the direction indicated in (2), the mechanical coupling is reduced since this will increase the mass, elasticity and internal resistance of the handle. The selection of material for the hand set handle will depend upon the ratio of the modulus of elasticity to the density of material, as well as its internal damping or molecular friction 120 under flexural strain. If the ratio of the modulus of elasticity to density be alone considered, it has been found that, metals, such as aluminum or steel or their alloys are best suited as a handle for the hand set. There 125

are, however, other materials, such as phenol condensation products which possess a higher internal damping than metallic substances and for this reason are to be preferred in many cases.

The same considerations apply with equal force to the material to be used for the cases of the transmitter and receiver.

Referring to the drawings, Figs. 1 and 2 illustrate a hand set having a handle of I-beam construction; Figs. 3 and 4 represent the preferred construction for a hand set to accomplish the objects of the present invention; and Fig. 5 represents one method of securing the instrument cases to the handle of the hand set.

I have found that a hand set constructed as shown in Fig. 1 of the drawing in which 6 represents the receiver, 7 the transmitter 20 and 8 the handle, sufficiently meets the requirements as set forth hereinabove for the production of a hand set which will give a maximum efficiency of operation without howling. Such a construction, however, is 25 not a desirable one since the handle would be difficult to grasp and since it is not ornamental. The essential features of such a construction, however, may be embodied in a form such as that shown in Figs. 3 and 4 30 which is suitable for use. In Fig. 3 the handle is shown as being made in one piece with the receiver and transmitter cases. Such a construction, while being the best for use, is somewhat difficult to manufacture. 35 For this reason it has been found more desirable to make the handle and instrument cases separately and attach them together in the manner as shown in Fig. 5. In this figure, the receiver case is fastened to the handle 11 by means of the screws 10, the paper washer 9 being inserted therebetween. This washer serves to compensate for any unevenness in the surfaces of the case and handle. Any other manner producing rigid 45 clamping between the instrument cases and the handle may be used.

By proceeding in accordance with the considerations hereinabove stated, I have been able to produce a telephone hand set 50 having:

1. A handle, which with the receiver and transmitter attached, has but one resonance to transverse waves below a frequency of 1800 cycles per second.

55 2. Other parts and joints which do not resonate below 1800 cycles per second.

The maximum uni-directional mutual impedance of such a set occurs at a frequency higher than 1800 cycles per second.

60 In order to connect the transmitter and receiver electrically, it is found convenient when a non-conducting material is used for the handle to imbed the electrical conductors therein. It is also desirable to imbed

suitable metal parts in such a handle to secure the instrument cases thereto. A handle having such inserts, however, is considered to be a one-piece handle, provided that it is not longitudinally discontinuous 65 between the instrument cases. 70

What is claimed is:

1. A unitary structure comprising a transmitter, a receiver and a support therefor, and having its maximum uni-directional mutual impedance at a frequency 75 higher than 1800 cycles per second.

2. A unitary structure comprising transmitting and receiving members, and a support therefor, said support having a frequency of fundamental mode of vibration 80 exceeding approximately 1000 cycles per second.

3. A unitary structure comprising transmitting and receiving members, and a support therefor, said support having but one 85 resonance to transverse waves below a frequency of 1800 cycles per second.

4. A unitary structure comprising a highly efficient transmitter and a receiver, and a handle with a frequency of fundamental mode of vibration exceeding approximately 1,000 cycles per second.

5. A telephone hand set comprising a handle with a frequency of fundamental mode of vibration exceeding approximately 95 1000 cycles per second and all of the joints of said hand-set being of high elasticity and resonating not below 1800 cycles per second.

6. A telephone hand set comprising a handle, receiver and transmitter cases attached thereto, said receiver and transmitter cases having no resonance below 1800 cycles per second.

7. A telephone hand set comprising a handle, receiver and transmitter cases attached thereto, the joints between said handle and said cases having no resonance below 1800 cycles per second.

8. A telephone hand set comprising a handle in one piece, having a frequency of 110 fundamental mode of vibration exceeding approximately 1,000 cycles per second.

9. A telephone hand set comprising a handle in one piece, receiver and transmitter cases attached thereto, said receiver and transmitter cases having no resonance below 1800 cycles per second.

10. A telephone hand set comprising a handle having means imbedded therein to secure instrument cases thereto, said handle having but one resonance to transverse waves below a frequency of 1800 cycles per second.

11. A telephone hand set comprising a handle composed of electrical non-conducting material, said handle having but one resonance to transverse waves below a frequency of 1800 cycles per second.

12. A telephone hand set comprising a handle composed of phenol condensation product, said handle having but one resonance to transverse waves below a frequency of 1800 cycles per second.
13. A telephone hand set comprising a receiver, a transmitter, a handle having a radius of gyration such that its fundamental mode of vibration exceeds approximately 1000 cycles per second, and joints between said receiver and said handle and between said transmitter and said handle of said hand set of high elasticity and resonating at a frequency above 1800 cycles per second.
14. A telephone hand set comprising a handle, a receiver case, and a transmitter case attached thereto, said receiver and transmitter cases being formed of a highly elastic material of such thickness that the fundamental mode of vibration exceeds 1800 cycles per second.
15. A telephone hand set comprising a transmitter, a receiver, and a common supporting means, said means comprising an elastic body having a radius of gyration such that its fundamental mode of transverse vibration exceeds approximately 1000 cycles per second.
16. A telephone hand set comprising a transmitter, a receiver, and common supporting means, said means comprising an elastic body having a radius of gyration such that it has but one resonance to transverse waves below a frequency of 1800 cycles per second.

In witness whereof, I hereunto subscribe my name this 22nd day of December A. D., 1920.

ALFRED S. CURTIS.
